CHUSETTS, A CORPORATION OF MASSACHUSETTS

GARMENT PACKAGE

Application filed May 3, 1926. Serial No. 106,586.

This invention relates to the packaging of garments and has particular reference to means for holding men's shirts in good condition for display in stores or for delivery 5 from a laundry.

The object of the invention is to enable a shirt to be exhibited or examined while in folded condition and maintained smoothly and with sufficient stiffness to enable it to 10 be quite freely handled without becoming crumpled.

Of the accompanying drawings:—

Figure 1 is a plan view of the stiffener which is to be assembled with a shirt. 15 Figures 2 and 3 are, respectively, front and rear views of a complete package, comprising a folded shirt with a stiffener secured in position relatively thereto.

Figure 4 represents a section on line 4—4 20 of Figure 2, on a larger scale.

Similar reference characters designate similar parts or features in all of the views.

Referring first to Figure 1, a flat piece of suitable material such as card board 12 is provided at one end with an integral foldable extension or flap 13. Preferably said flap 25 is tapered. For the sake of economy in the amount of material employed for each member 12, 13, the lower end of the section 12 is recessed as at 14. This enables a plurality of the stiffeners to be cut from a strip of material with practically no waste. The recess 30 14, besides providing for economy in the amount of material required to make the

stiffeners, as just explained, facilitates separation of the shirt and stiffener when desired to do so while retaining the shirt in its smooth folded condition. To effect such separation, that portion of the folded shirt 35 40 which traverses the recess 14 is grasped and held by one hand while the other hand pulls the stiffener out after, of course, loosening the cord 16, and such separation need not disturb the smooth folded condition of the shirt.

The tip of the flap 13 is slotted to provide a foldable ear 15 which overlaps a piece of cord or string 16, said ear being secured by suitable adhesive in folded condition so as 45 50 maintain the string in position with its two

ends ready to be tied as hereinafter described, after the flap 13 has been folded on the crease line *x*.

Preferably the section 12 of the stiffener is provided with longitudinal creases *y* near 55 its side edges so that when a shirt is folded around said section sufficiently closely to slightly contract the section laterally, the margins of the section will be bent somewhat angularly relatively to the plane of the main 60 portion of the section and impart longitudinal stiffness to said section.

To provide such a package as illustrated by Figures 2, 3 and 4, a shirt *a* the neck band of which is illustrated at *a'*, is folded around the 65 section 12 and then the flap 13 is folded on its crease line *x* over and onto a portion of the back of the shirt (Fig. 3), and then the ends of the string 16 are brought together 70 and tied as at 17.

The above described operation of assembling the shirt and stiffener and securing them together is effected in a very short time; less time, in fact than is usually required to fold a shirt and pin it in folded condition. 75 The shirt can be readily examined as fully as though no stiffener was employed, and when dis-assembling is to be effected a simple untying of the knot 17 or cutting of the string enables the shirt to be shook out free from 80 the stiffener in condition to be put on the wearer.

Having now described our invention, we claim:

1. The combination with a folded shirt, 85 of means for holding it in smooth condition with its bosom portion exposed, said means comprising a main stiffener section having a recess at one end and having an integral flap projecting from its opposite end, the said 90 recess and flap being of the same contour and size, said flap being folded against the back of the shirt and secured in that position.

2. A stiffener for a folded garment, said 95 stiffener comprising a main section having a recess at one end and having a foldable flap extending from its opposite end, said flap and recess being of the same contour, the tip of said flap carrying a cord having a length 100

to be fastened around both the stiffener and a garment associated with said stiffener.

3. The combination with a folded garment, of means for holding it in smooth condition, said means comprising an elongated stiffener section having an integral flap extending from one end and narrower than the said section, the garment being folded around said section and exposed on both surfaces thereof, and the flap being folded against an outer surface portion of the garment, the other end of said stiffener section having a recess to facilitate separation of the shirt from its enclosed stiffener.

15 In testimony whereof we have affixed our signatures.

LEON E. LA BOMBARD.
MELVIN H. SIDEBOOTHAM.
